KNEE REST

Clair L. Myers, Chicago, Ill.

Application September 30, 1948, Serial No. 148,882

Term of patent 3½ years

(Cl. D15—8)

To all whom it may concern:

Be it known that I, Clair L. Myers, a citizen of the United States, residing at Chicago, in the county of Cook and State of Illinois, have invented a new, original, and ornamental Design for a Knee Rest, of which the following is a specification, reference being had to the accompanying drawing, forming part thereof.

I claim:

The ornamental design for a knee rest, substantially as shown.

CLAIR L. MYERS.
